United States Patent Office.

MILES WATERHOUSE, OF PASSAIC, NEW JERSEY.

Letters Patent No. 78,559, dated June 2, 1868.

IMPROVED APPARATUS FOR DYEING.

The Schedule referred to in these Letters Patent and making part of the same.

TO ALL WHOM IT MAY CONCERN:

Be it known that I, MILES WATERHOUSE, of Passaic, in the county of Passaic, in the State of New Jersey, have invented certain new and useful Improvements in Apparatus for Dyeing; and I hereby declare the following to be a full and exact description thereof, reference being had to the accompanying drawings, and to the letters of reference marked thereon.

Figure I is a sectional elevation of the dye-vat, with its supplemental perforated bottom, and steam and liquid-pipes, all to be further hereinafter described.

Figure II is a sectional horizontal plan, taken on the line a.

Figure III is a top or horizontal view of the dye-vat.

To the ordinary dye-vat A, having a perforated or supplemental bottom, B, elevated a short distance above the bottom of the vat, I attach one or more liquid or vomiting-tubes, C, into the lower ends of which I introduce the nozzles of the steam-tubes D D. These tubes are connected properly to a steam-boiler at any convenient distance, and supplied with valves proper for the admission and control of the steam. I put sufficient water, and such drugs or dye-stuffs as are necessary, for the colors to be produced, into the bottom of the vat, the liquid rising a little way above the supplemental bottom. I then pack the wool, yarns, cloth, or other material to be dyed into the vat above the supplemental bottom, as solidly as they can be trodden by men. I then turn on the steam, which, discharged from the nozzles D' D', acts in the manner of an ejection-pump upon the liquid below the supplemental bottom, and forces it upwards and outwards at the nozzles E E of the vomiting-pipes, falling on the exposed surface of the material being dyed.

By the displacement of the liquid beneath the supplemental bottom, a partial vacuum is produced; and the atmospheric pressure, acting on the upper surface of the goods, and fluids projected thereon by the nozzles E E, forces those fluids down through the goods, towards the vacuous space, beneath the supplemental bottom; and thus, so long as steam is admitted, a circulation of the liquid dye-stuffs down through the goods, and up through the vomiting-tubes may be continued.

I find in practice that the oxygen necessary to the production of certain colors, and which is absorbed from the atmosphere by exposure of the goods, during the ordinary process of dyeing, to the action of the air, may be communicated without such exposure and handling necessary thereto, by successive exposures of the fluid dye in small or divided streams to the same influence, and repeatedly passing the liquid through the goods, as and in the manner before described.

By this process and arrangement I effect a great economy in both the mordant-salts and the coloring-matters, as much less water requires to be impregnated with those coloring-matters and salts, and, after completion, the residue is so small as scarcely to be appreciable. I also effect an economy in fuel, as it is necessary to heat only a small volume of water in order to dye a very large vatful of material. The economy in labor I also find is quite considerable, as no stirring or handling during the process is necessary. I also find that the color is imparted to the goods in a more even and perfect manner, and that no tangling or matting of fibres or yarns is the result, as is the case by the ordinary methods of dyeing.

I claim the combination and arrangement of the several parts, substantially as and for the purposes shown and described.

MILES WATERHOUSE.
